COUNTERROTATIONAL AIR FLOW
GUN TYPE OIL BURNER

Thomas W. Murphy, Narberth, Pa., assignor to
Monarch Manufacturing Works, Inc., Philadelphia, Pa., a corporation of Delaware

Application September 4, 1946, Serial No. 694,752

6 Claims. (Cl. 158—76)

1

This invention relates to an oil burner of the type shown in my application Serial No. 650,859, filed February 28, 1946, and has particular reference to improved means insuring proper relationship of the combustion air to the oil stream or spray to insure uniform and proper combustion.

Difficulties have heretofore been experienced in securing the proper uniform flame in oil burners by reason of the fact that there is interference with the stream of air by the ignition electrodes and the oil line. As a result of unequal distribution of the air, there may exist substantial asymmetry of the flame, i. e., it may start on one side, as viewed from above, several inches closer to the cone ring than on the other side, with a resulting uneven distribution of heat in the furnace.

In accordance with the present invention, air guiding means are provided for the purpose of insuring uniformity of the air stream and proper directing thereof relative to the oil spray.

The foregoing general object of the invention, as well as other objects particularly relating to details, will become apparent from the following description read in conjunction with the accompanying drawing, in which:

Figure 1 is a vertical section through an oil burner embodying the invention;

Figure 2 is a vertical section taken on the plane indicated at 2—2 in Figure 1; and

Figure 3 is a vertical section taken on the plane indicated at 3—3 in Figure 1.

A blow tube 2 of conventional character receives air from the usual blower fan 4 provided with blades 6. At the end of the blow tube or head of the burner, there is a cone or choke ring 8 which is secured to the end of the blow tube in any desired manner, and abutting the choke ring is an annular air diffuser or mixing head 10. The front end of the diffuser is provided with a free opening whose diameter is somewhat greater than the opening in the choke ring 8 and is provided with a closed back or rear end with the exception of several small air passages herein-after described.

The diffuser or mixing head 10 is provided with a series of inwardly extending curved blades 12, the end of the diffuser or mixing head 10 is centered by engagement in the choke ring 8 and prevents the passage of air between the choke ring 8 and the mixing head. Mounted on the mixing head 10 is a ring 15 which is shown in an extreme forward position covering a portion of the openings between the blades 12 as well as a portion of the cylindrical portion of the mixing head

2

beyond the blades 12 so that all of the air delivered to the mixing head which passes between the blades thereto passes back of the ring 15. There is an annular air space between the inner wall of the blow tube and the periphery of the diffuser, and extending from the rear wall of the diffuser are a plurality of projections 14 for centering and supporting the rear end thereof in the blow tube.

Extending forwardly from the rear end of the diffuser is a stabilizer ring 16, the inner wall of which is concentric with the axis of the diffuser, while the outer wall or periphery of the stabilizer ring slopes inwardly and toward the open end of the diffuser 10, and meets the inner wall of the ring, forming a sharp annular edge. Extending through the rear wall of the diffuser 10 are a plurality of openings 18, which extend at such an angle as to give the air passing through the back of the diffuser 10 a twirling motion in a reverse direction to that given to the air passed between the blades 12, some of which passes over the outer face or tapered wall of the ring.

Extending axially through a tubular supporting member 20 which may be formed integrally with the back of the diffuser, is an oil line 22 terminating in the usual spray nozzle 24. Porcelain insulator tubes 26 are mounted in spaced tubular supports 28 also extending from the back of the diffuser for ignition wires 30.

By reason of the foregoing described construction, there is provided presentation of the combustion air to the oil spray whereby a symmetrical flame is produced.

Due to the inwardly curved blades 12 of diffuser or mixing head 10, the air is given an axial and twirling tangential flow due to the restricted area between edges of blades 12 and the forwardly converging face of the periphery of the stabilizer ring 16 causing a portion of the air stream under pressure to flow first with a substantial radial component of flow against the forwardly converging face of the ring 16, and then to be directed at an angle into the swirling column of air delivered by the blades 12 immediately in advance of ring 16 between the edge of the ring 16 and the inner diameter of blades 12 causing a turbulence toward the center of the mixing head to at least partially break down the evacuated space around and ahead of the oil spray nozzle 24. The converging air streams or mixture is then compressed by the choke ring 8 and is then expanded equally in all directions as it leaves the mixing head, after passing the reduced opening 55 in the choke ring, thus providing an evenly mixed

combustible gas beyond the choke ring outlet. However, in all instances, this is not sufficient to properly break the vacuum just around and ahead of the nozzle 24; therefore, these two means just referred to above, must be supplemented with properly directed air and of suitable volume through diagonal holes (or slots) so arranged as to produce still more central disturbance within the mixing head.

If a relatively small portion of air is passed through openings 18 to cause a twirling of air in the core of the stream in a reverse direction from the twirling caused by the blades 12, a slightly greater agitation of the air stream about the end of the spray nozzle, will be produced, thus improving the mixture of the oil spray and air beyond the nozzle 24.

The construction of the combined diffuser and stabilizer ring can readily be made by shearing and pressing the blades from the wall of a cylinder, and mounting one end thereof on the end of a cast member, having the stabilizer ring and supporting members 14 cast integrally with the end enclosure.

What I claim and desire to protect by Letters Patent is:

1. In combination, a nozzle for providing an oil spray and means for directing air to the spray of oil to support combustion thereof, said means including a blow tube, a convergent cone ring terminating the blow tube beyond the nozzle, a hollow cylindrical wall forming a diffuser extending axially about the nozzle, said diffuser having a discharge end of greater diameter than the outlet from the cone ring, engaging the cone ring and having a substantially closed rear end, said cylindrical wall including a plurality of spaced blades around the periphery thereof, the blades being arranged non-radially to cause the air passing between them to be given a whirling motion during passage into the diffuser, and an annular wall forming a stabilizer extending axially forwardly from the rear end of the diffuser between the nozzle and the blades, there being a plurality of air passages through the rear end of the diffuser within the stabilizer directed to cause the air passing therethrough to be given a whirling motion during its passage into the diffuser in a reverse direction to the whirling motion given to the air passing through the blades around the periphery of the diffuser, the stabilizer being located with respect to the two air flows to cause a convergence of the air flows in the region of the nozzle.

2. In combination, a nozzle for providing an oil spray and means for directing air to the spray of oil to support combustion thereof, said means including a blow tube, a convergent cone ring terminating the blow tube beyond the nozzle, a hollow cylindrical wall forming a diffuser extending axially about the nozzle, said diffuser having a discharge end of greater diameter than the outlet from the cone ring, engaging the cone ring and having a substantially closed rear end, said cylindrical wall including a plurality of spaced blades around the periphery thereof, the blades being arranged non-radially to cause the air passing between them to be given a whirling motion during passage into the diffuser, a ring mounted externally on the diffuser limiting the portion of the diffuser to which air is admitted between the blades, and an annular wall forming a stabilizer extending axially forwardly from the rear end of the diffuser between the nozzle and the blades, there being a plurality of air passages through

the rear end of the diffuser within the stabilizer directed to cause the air passing therethrough to be given a whirling motion during its passage into the diffuser in a reverse direction to the whirling motion given to the air passing through the blades around the periphery of the diffuser, the stabilizer being located with respect to the two air flows to cause a convergence of the air flows in the region of the nozzle.

3. In combination, a nozzle for providing an oil spray and means for directing air to the spray of oil to support combustion thereof, said means including a blow tube, a convergent cone ring terminating the blow tube beyond the nozzle, a hollow cylindrical wall forming a diffuser extending axially about the nozzle, said diffuser having a discharge end of greater diameter than the outlet from the cone ring, engaging the cone ring and having a substantially closed rear end, said cylindrical wall forming a plurality of spaced blades around the periphery thereof, the blades being arranged non-radially to cause the air passing between them to be given a whirling motion during passage into the diffuser, and an annular wall forming a stabilizer having a conical periphery extending axially forwardly from the rear end of the diffuser between the nozzle and the blades, there being a plurality of air passages through the rear end of the diffuser within the stabilizer directed to cause the air passing therethrough to be given a whirling motion during its passage into the diffuser in a reverse direction to the whirling motion given to the air passing through the blades around the periphery of the diffuser, the stabilizer being located with respect to the two air flows to cause a convergence of the air flows in the region of the nozzle.

4. In combination, a nozzle for providing an oil spray and means for directing air to the spray of oil to support combustion thereof, said means including a blow tube, a convergent cone ring terminating the blow tube beyond the nozzle, a hollow cylindrical wall forming a diffuser extending axially about the nozzle, said diffuser having a discharge end of greater diameter than the outlet from the cone ring, engaging the cone ring and having a substantially closed rear end, said cylindrical wall including a plurality of spaced blades around the periphery thereof, the blades being arranged non-radially to cause the air passing between them to be given a whirling motion during passage into the diffuser, and an annular wall forming a stabilizer extending axially forwardly from the rear end of the diffuser and terminating back of the end of the nozzle between the nozzle and the blades, there being a plurality of air passages through the rear end of the diffuser within the stabilizer directed to cause the air passing therethrough to be given a whirling motion during its passage into the diffuser in a reverse direction to the whirling motion given to the air passing through the blades around the periphery of the diffuser, the stabilizer being located with respect to the two air flows to cause a convergence of the air flows in the region of the nozzle.

5. In combination, a nozzle for providing an oil spray and means for directing air to the spray of oil to support combustion thereof, said means including a blow tube, a convergent cone ring terminating the blow tube beyond the nozzle, a hollow cylindrical wall forming a diffuser extending axially about the nozzle, said diffuser having a discharge end of greater diameter than the outlet from the cone ring, engaging the cone ring and having a substantially closed rear end,

said cylindrical wall including a plurality of spaced blades around the periphery thereof, the blades being arranged non-radially to cause the air passing between them to be given a whirling motion during passage into the diffuser, a ring mounted externally on the diffuser limiting the portion of the diffuser to which air is admitted between the blades, and an annular wall forming a stabilizer extending axially forwardly from the rear end of the diffuser and terminating back of the end of the nozzle between the nozzle and the blades, there being a plurality of air passages through the rear end of the diffuser within the stabilizer directed to cause the air passing therethrough to be given a whirling motion during its passage into the diffuser in a reverse direction to the whirling motion given to the air passing through the blades around the periphery of the diffuser, the stabilizer being located with respect to the two air flows to cause a convergence of the air flows in the region of the nozzle.

6. In combination, a nozzle for providing an oil spray and means for directing air to the spray of oil to support combustion thereof, said means including a blow tube, a convergent cone ring terminating the blow tube beyond the nozzle, a hollow cylindrical wall forming a diffuser extending axially about the nozzle, said diffuser having a discharge end of greater diameter than the outlet from the cone ring, engaging the cone ring and having a substantially closed rear end, said cylindrical wall including a plurality of spaced blades around the periphery thereof, the

blades being arranged non-radially to cause the air passing between them to be given a whirling motion during passage into the diffuser, and an annular wall forming a stabilizer having a conical periphery extending axially forwardly from the rear end of the diffuser and terminating back of the end of the nozzle between the nozzle and the blades, there being a plurality of air passages through the rear end of the diffuser within the stabilizer directed to cause the air passing therethrough to be given a whirling motion during its passage into the diffuser in a reverse direction to the whirling motion given to the air passing through the blades around the periphery of the diffuser, the stabilizer being located with respect to the two air flows to cause a convergence of the air flows in the region of the nozzle.
